UNITED STATES PATENT OFFICE

141,620

DESIGN FOR A COMBINED LAVATORY AND VANITY

Jacques Stanitz, Warren, Ohio, assignor to Mullins
Manufacturing Corporation, Salem, Ohio, a corporation of New York

Application March 26, 1945, Serial No. 118,691

Term of patent 14 years

(Cl. D4—2)

To all whom it may concern:

Be it known that I, Jacques Stanitz, a citizen of the United States, residing at Warren, in the county of Trumbull and State of Ohio, have invented a new, original, and ornamental Design for Combined Lavatory and Vanity, of which the following is a specification, reference being had to the accompanying drawing, forming part thereof.

The figure is a perspective view of a combined lavatory and vanity showing my new design. The characteristic features of my design are shown by means of full lines in the drawing.

I claim:

The ornamental design for a combined lavatory
and vanity, substantially as shown and described.

JACQUES STANITZ.
